UNITED STATES PATENT OFFICE.

EDWARD SMITH DINKEL, OF BRIDGEWATER, VIRGINIA.

CURTAIN-SUPPORT.

No. 920,440.

Specification of Letters Patent.

Patented May 4, 1909.

Application filed November 14, 1907. Serial No. 402,175.

To all whom it may concern:

Be it known that I, EDWARD S. DINKEL, a citizen of the United States, residing at Bridgewater, in the county of Rockingham 5 and State of Virginia, have invented a new and useful Curtain-Support, of which the following is a specification.

This invention relates to means for supporting curtains, shades, and the like, and 10 is particularly intended for mounting on the upper sash of a window so that the curtain will be raised and lowered with the sash in order to admit light and air thereover.

The primary object of the present invention is to provide novel, simple and practicable means that can be readily applied by an unskilled person to any ordinary sash, and is easily adjusted so that it will properly coöperate with the window frame, regardless 20 of the width and thickness of the same.

The preferred form of construction is illustrated in the accompanying drawings, wherein:—

Figure 1 is a perspective view of the upper 25 portion of a frame and window sash showing a pair of supports in place on the latter. Fig. 2 is a horizontal sectional view, showing one of the supports in top plan. Fig. 3 is a vertical sectional view on the line 3—3 of Fig. 2. Fig. 4 is a horizontal sectional view on the line 4—4 of Fig. 3. Fig. 5 is a detail face view of the outer arm of the second section. Fig. 6 is a sectional view on the line 6—6 of Fig. 5. Fig. 7 is a cross sectional view on the line 7—7 of Fig. 5. Fig. 8 is a detail sectional view on the line 8—8 of Fig. 7, but on an enlarged scale, the plate being removed. Fig. 9 is a similar view on the line 9—9 of Fig. 7.

Similar reference numerals designate corresponding parts in all the figures of the drawings.

In the embodiment illustrated, the frame of the window is designated 10, and may be 45 of any desired form or construction. In it slides the upper sash 11, and this sash carries a pair of curtain supports. As these supports are duplicates, but one will be described. The support comprises angularly 50 disposed extensible members, and is constructed as follows. An inner section 12 is provided having an offset ear 13, which is secured by screws 14 or other suitable fasteners to the sash. This section projects 55 outwardly from the sash, and has offset lips or hooks 15 on its upper and lower edges,

forming guideways, in which is slidably mounted one of a pair of angularly disposed arms 16 and 17 that form in connection with a vertical intermediate portion 18, a second 60 section. As shown, particularly in Figs. 3 and 4, the section 12 is provided on the face along which the arm 16 slides with a projection 19, and said arm has in its opposing face a plurality of sockets 20, adapted to receive the projection. It will thus be seen that while the arm can be adjusted, it is normally held against movement. The sections 12 and 16 constitute one of the extensible members.

The arm 17 projects outwardly outside the frame 10, and has upper and lower outstanding and overturned flanges 21 forming guideways, in which is slidably mounted the arm 22 of a third bracket. This bracket has an 75 outstanding arm 23. The bracket 22—23 constitutes a third section and the arms 17 and 22 constitute the second extensible member already mentioned. The bracket or third section is preferably, though not necessarily constructed of wire, and in the embodiment shown, is formed from a single piece. Starting at one end 24, a loop is formed, which constitutes the arm 22, and a second angularly disposed loop forms the 85 arm 23. This arm 23 terminates at its outer end in a pole holding hook 25, while the inner portion thereof is formed into an upper bar 26 and a lower bar 27. A coil 28 formed in the upper bar, produces a socket for the reception of the shade roller gudgeon, one of the sockets being angular, while the lower arm is doubled, forming spaced guide fingers 29 that are located on opposite sides of the margin of the curtain. The wire, after forming the two loops is coiled, as illustrated at 90 30 about the terminal 24, and is then brought down and the end thereof is coiled, as shown at 31 around the lower bar, forming an upright brace 32.

It will be evident that when a pair of these supports are secured to a sash, by sliding the arm 16 on the sections 12, the arms 17 can be properly positioned with respect to the window frame, regardless of the depth or 105 thickness of the latter. Then by sliding the arms 22 on the sections 17, the distance between the brackets can be varied to suit the width of the side bars of the frame, as well as the length of the curtain roller. The detachment of the arms 22 from the arms 17 is prevented by the cross bars 33 of the loops en-

gaging outstanding stop lugs 34 located at the outer ends of the arms 17, within said loops. When the curtain roller is placed in position, as indicated in dotted lines in Fig. 1, the shade or curtain will pass through the guides, formed by the fingers 29, and a curtain pole can be placed on the hooks 25. It will be evident that if desired, two gudgeon receiving sockets 28 and guides 29 can be formed in the arm, so that two curtains can be supported. With this structure therefore, if the upper sash is raised or lowered, the curtain will be raised or lowered with it, thus giving an unobstructed space above the curtain and sash for ventilation and for admission of light, while the curtain can be used to screen the lower portion of the window.

From the foregoing, it is thought that the construction, operation and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. In a device of the character described, the combination with an arm comprising a substantially flat face having outstanding flanges on its opposite edges, and also having outstanding stop lugs at one edge between the flanges, of means for securing the arm upon a window, and a curtain supporting

arm slidably mounted on the first mentioned arm and engaged with the flanges thereof, said curtain supporting arm having a cross bar at one end that is disposed transversely of the first mentioned arm and moves across the same, said movement being limited by said stop lugs.

2. In a device of the character described, a single outstanding bracket comprising upper and lower arms connected at their outer ends, the upper arm having a roller-gudgeon receiving socket, and the lower arm having spaced laterally extending guide fingers located below the socket.

3. In a device of the character described, a bracket comprising sections, one of which is arranged to be secured to a support, the other being formed of wire comprising angularly disposed arms, one of said arms being slidably mounted on the first section, the other having an upper gudgeon receiving socket, a curtain guide below the socket, and a pole holding hook outside the socket and guide.

4. In a device of the character described, a supporting bracket formed of wire having an upper arm looped to provide a roller gudgeon receiving socket, and a lower arm having spaced laterally offset doubled portions forming a curtain guide between them.

In testimony, that I claim the foregoing as my own, I have hereto affixed my signature in the presence of two witnesses.

EDWARD SMITH DINKEL.
